(57) **CLAIM**

The ornamental design for an umbrella stand, as shown and described.

DESCRIPTION

FIG. 1 is a front, top perspective view of an umbrella stand, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front, top perspective view of the umbrella stand of FIG. 1 showing an exploded view.

The broken lines show portions of the umbrella stand that form no part of the claimed design.
